HARRY BYRNS, OF HAMILTON, ONTARIO, CANADA, ASSIGNOR OF ONE-HALF TO
WILLIAM F. CONDON, OF HAMILTON, ONTARIO, CANADA.

APPARATUS FOR RAISING SUBMERGED BODIES.

1,164,067.

Specification of Letters Patent. Patented Dec. 14, 1915.

Application filed July 19, 1915. Serial No. 40,771.

To all whom it may concern:

Be it known that I, HARRY BYRNS, of the city of Hamilton, in the county of Wentworth, Province of Ontario, Dominion of Canada, have invented certain new and useful Improvements in Apparatus for Raising Submerged Bodies, of which the following is a specification.

My invention relates to improvements in the apparatus for raising ships or other submerged bodies and the object of the present invention is to devise an apparatus for performing this operation which is simpler, cheaper and more efficient than those formerly in use; a further object is to devise means by which the water may be expelled from the various compartments of the ship thus increasing the buoyancy to such an extent that the ship will float; a further object is to devise a means for raising ships which is more easily employed than former systems; and a still further object is to provide means whereby the medium employed to raise the ship may be readily removed therefrom.

My invention consists of the construction and arrangement of parts all as hereinafter more particularly described and illustrated in the accompanying drawings, in which:

30 Figure 1 shows an elevational view of my apparatus as employed in raising a submerged ship. Fig. 2 is a submerged ship as shown in Fig. 1 with some portions broken away. Fig. 3 is an enlarged sectional plan showing a compartment of a submerged ship.

Like characters of reference indicate corresponding parts in the different views.

1 is a submerged ship.
40 2 is the surface of the water.
3 are large inflatable bags or balloons having a receiving portion 4 and a safety valve 5. These bags are suitably secured to the ship by means of the chains or cables 6.
45 7 is an air compressor or pump supported at the surface on a float 8.

9 are tubes connecting the compressor and the balloons 3 and secured to the latter in the receiving portion 4.

50 9¹ are suitable valves in these tubes adjacent to their upper ends at which they are attached to the compressor.

10 is an inflatable bag made of strong waterproof material and having a safety valve 11 (see Fig. 3) and a receiving portion

12 provided with a check valve 12^x into which is fitted the end of the inflating tube 9.

13 are the port holes of the ship.

14 are main pipes laid in the ship by the device and comprising the cross pipes 14¹ 60 and 14² and a plurality of pipes 14³ extending longitudinally of the ship and connecting the pipes 14¹ and 14² together.

15 are branch pipes coupled at one end to the pipes 14³ at suitable intervals and at 85 the opposite end to the receiving portion 12 of the bags 10.

16 is a globe valve for controlling the flow through the pipes 15.

17 is a pipe leading from the compressor 7 70 to the pipe 14¹.

18 is an outlet provided with a closing valve 19.

The procedure followed in employing my method is as follows: The empty bags or 75 balloons 3 are submerged and attached to the ship in any suitable manner. The chains 6 may be fastened directly to the port holes as shown at A, Fig. 1, or they may be passed completely around the ship 80 as shown at B, Fig. 1. The bags are then inflated from the surface by means of the compressor 7. Bursting of the bags is prevented by means of the safety valves 5.

After inflation the valves 9¹ are closed and 85 the tubes 9 may then be disconnected from the compressor. Any number of these bags or balloons 3 may be employed depending upon the size of the ship. The buoyancy is further increased by displacing the water 90 from the interior of the ship. This is accomplished by means of any number of air bags 10 which may be made of any size and shape. These bags 10 in the deflated condition are inserted into the various compartments as shown at C, Fig. 2. The pipes 14¹, 14², 14³ and 15 are then laid and connected. The globe valves 16 are closed and the pipe 17 attached the valve 19 being opened.

By this means water in the pipes 100 14¹ and 14² and 14³ is all blown out. The valve 19 is then closed and the valve 16 opened inflating the bags 10 which then assume approximately the form of the compartment and displaces the water therefrom. After inflation their inflating tubes may be removed from the compressor after closing the corresponding valves 9¹ in such tubes. The safety valves 11 in these bags prevent bursting of the same.

A sufficient number of the bags 10 are employed to increase the buoyancy of the ship to a sufficient degree to enable it to float, after which it may be towed to any suitable point.

After the ship has been safely raised and suitably located the bags 3 and 10 may be readily removed. The operation of expelling the air therefrom is accomplished easily 10 by simply opening the various valves 9¹.

From the foregoing it will be seen that my invention provides a very simple and effective means whereby a ship of any dimensions may be floated and furthermore the 15 labor entailed is very small since it is only necessary for a diver to insert the deflated bags in the various compartments after which they are inflated. Further the removal of the bags from the raised ship is 20 very simply accomplished.

What I claim as my invention is:

1. An apparatus for raising a submerged body having a plurality of compartments therein, comprising main pipes extending 25 crosswise of the interior of the body at each end, pipes extending longitudinally of the body between the compartments thereof and connected to the cross pipes, means for

forcing compressed air into the pipes and an inflatable bag located in each compartment, a pipe connection between each bag and the main pipes, means for forcing the water out of the pipes after being connected to the air supply and means for keeping the water out of the inflatable bags while the 30 water is being forced out of the main pipes.

2. An apparatus for raising a submerged body having a plurality of compartments therein, comprising main pipes extending crosswise of the interior of the body at each 35 end one being provided with an inlet and the other with an outlet, pipes extending longitudinally of the body between the compartments thereof and connected to the cross pipes, means for forcing compressed air into 40 the inlet of the cross pipe and an inflatable bag located in each compartment, a pipe connection between each bag and the main pipes, a closing valve in each pipe connection and a closing valve for the outlet of the 45 other cross pipe.

HARRY BYRNS.
